(57) **CLAIM**

The ornamental design for the pet training harness, as shown and described.

DESCRIPTION

FIG. 1 is a front view of the pet training harness showing my new design;

FIG. 2 is a rear view thereof;

FIG. 3 is a top-plan view thereof;

FIG. 4 is a bottom plan view thereof;

FIG. 5 is a left-side view thereof; and,

FIG. 6 is a right-side view thereof.

The dotted lines showing pet training harness attachment components do not form part of the claim and are shown to assist in understanding the invention.
